[57] CLAIM

The ornamental design for an automobile serving tray,
substantially as shown and described.

DESCRIPTION

FIG. 1 is a top plan view of an automobile serving tray
showing my new design.

FIG. 2 is an elevational view of one end thereof, a view
of the opposite end being a mirror image thereof.

FIG. 3 is an elevational view of one side thereof.

FIG. 4 is an elevational view of the opposite side
thereof.

FIG. 5 is a bottom plan view thereof.
